[57] CLAIM

The ornamental design for a hanging lamp, as shown
and described.

DESCRIPTION

FIG. 1 is a front perspective view of a hanging lamp
according to the present invention, wherein the lamp is
symmetrical so that rear and side views are substantially
identical to the view of FIG. 1;
FIG. 2 is a top plan view of the lamp of FIG. 1; and,
FIG. 3 is a bottom plan view of the lamp of FIG. 1.

FIG. 1.

Fig. 2.

Fig. 3.
